UNITED STATES PATENT OFFICE

98,552

DESIGN FOR A PORTABLE RADIO CABINET OR SIMILAR ARTICLE

Raymond Franklin Stewart, South Pasadena,
Calif.

Application July 20, 1934, Serial No. 52,647

Term of patent 3½ years

To all whom it may concern:

Be it known that I, Raymond F. Stewart, a citizen of the United States, residing at South Pasadena, in the county of Los Angeles, State of California, have invented a new, original, and ornamental Design of a Portable Radio Cabinet or Similar Article, of which the following is a specification, reference being had to the accompanying drawing, forming part thereof.

Figure 1 is a front elevation of the design.
Figure 2 is an end view partly in perspective.

I claim—

The ornamental design for a portable radio cabinet or similar article as shown.

RAYMOND FRANKLIN STEWART.
